Primary Examiner — Lauren D Mcvey*Assistant Examiner* — Elisa Maria Pujals(74) *Attorney, Agent, or Firm* — Carter, DeLuca & Farrell LLP(57) **CLAIM**

The ornamental design for a triangular volleyball net, as shown and described.

DESCRIPTION

FIG. 1 is a perspective view of a triangular volleyball net in accordance with the present design;

FIG. 2 is a front view of the triangular volleyball net of FIG. 1;

FIG. 3 is a rear view of the triangular volleyball net of FIG. 1;

FIG. 4 is a top view of the triangular volleyball net of FIG. 1;

FIG. 5 is a right side view of the triangular volleyball net of FIG. 1;

FIG. 6 is a bottom side view of the triangular volleyball net of FIG. 1; and,

FIG. 7 is a left side view of the triangular volleyball net of FIG. 1.

The broken lines in the drawings depict portions of the triangular volleyball net that form no part of the claimed design.

1 Claim, 7 Drawing Sheets(56)
